SAMUEL D. SOLOMON, OF LANSING, MICHIGAN

METHOD AND APPARATUS FOR PLACING ROAD BEDS OR FOUNDATIONS IN SINK HOLES

Application filed December 22, 1930. Serial No. 503,881.

The objects of the invention are:

First, to effectively displace the muck from under a dirt filling or from beneath any foundation.

5 Second, to provide improved hydraulic means for the purpose.

Third, to provide an effective apparatus for the purpose.

Objects pertaining to details and economies 10 of construction and operation will appear from the description to follow. I accomplish the objects of my invention by the device shown in the accompanying drawings, in which:

15 Fig. 1 is a cross sectional view of a highway under construction, showing the method of displacing the muck from beneath the fill where the road is, for instance, being built over a marshy strip.

20 Fig. 2 is a detail longitudinal sectional view showing a road bed being laid across a muck sink hole.

Fig. 3 is a diagrammatic view showing how 25 the muck is removed from under a fill.

Fig. 4 is a fragmentary view partially in section of one of the hydraulic and compression devices.

The parts will be identified by their numerals of reference which are the same in all 30 the views.

1 is a roadway fill. 2 is the muck layer which constitutes the soft, yielding material causing a sink hole. 3 is a hydraulic casing, preferably of three-inch pipe, which is inserted down through the fill to the muck layer beneath. 4 is a removable cap therefor provided with a stuffing box 5. 6 is a water pipe 35 extending through the stuffing box 5 and provided with perforations 7 at the lower end.

40 8 is a header pipe for delivering water under pressure, preferably from 60 to 100 lbs., the pressure being supplied directly by a pump (not shown) or from any suitable water main.

The header is preferably connected by 45 compression hose 9 through elbow 10 to the hydraulic compression pipes 6.

In carrying out my improved method, filling dirt is deposited in mass and bulk considerably above the road level line. After it 50 has had time to settle, I drive through the

filling dirt the pipes 3 and introduce into them the hydraulic pipes 6, putting on pressure so that water flows freely out through the perforations 7 and rises through the pipe 3 carrying with it the suspended muck until 55 there is a cavity 11 formed around the bottom of each one of the pipes. The perforated part of each pipe 6 projects below the corresponding pipe 3.

The caps 4 are then put in place and 60 screwed down tightly, sealing the casing and making a joint that is water tight. Pressure is then turned on to the entire group of pipes, the pressure being from 60 to 100 lbs. per square inch. The casings are firmly retained 65 in the filling dirt, the muck is gradually completely saturated with water and becomes semifluid, and the weight of the filling dirt compresses the same laterally so that it is forced out at each side of the road or at each 70 side of the fill. Dirt is then added until the fill has dropped down to the bed rock through the muck, and thus has become stable.

The same method can be used for a foundation that it has been necessary to place on 75 a muck sink hole or base.

The casings should be inserted four to six feet apart or further in all directions so as to deliver a large quantity of water to thoroughly soften the muck.

80 I have described my invention in its preferred form. I desire to claim it specifically as shown and also broadly as pointed out in the appended claims.

Having thus described my invention, what 85 I claim as new and desire to secure by Letters Patent is:

1. The method of displacing muck under a fill or a foundation, consisting in introducing a casing downwardly so that it is open and extends into the muck and its upper end extends above the filling, introducing water under pressure through a pipe perforated at the bottom to displace and flush out a quantity of the muck below the end of the casing, 90 and then closing the casing around the pipe and applying heavy pressure to the soaked muck to cause it to move and flow from under the fill or foundation.

2. The method of displacing muck from 100

under a fill or a foundation, consisting in saturating the muck with water and applying heavy pressure to cause its lateral flow and displacement from beneath the fill or foundation.

- 3. In an apparatus for displacing muck from a sink hole beneath a road bed or foundation, the combination of a casing, a hydraulic pipe perforated at its lower end to be introduced into said casing with the perforated part of said pipe projecting below the casing, a removable cap for sealing the upper end of said casing, and means for delivering water under pressure to said hydraulic pipe.
- 4. The method of displacing muck from under a fill or foundation consisting of placing filling or foundation material upon the muck, passing water conduits through the filling material into the muck below the same, and discharging water under pressure into the muck whereby it is reduced to semi-fluid flowing condition.
- 5. The method of displacing muck from under a fill or foundation consisting of placing the fill or foundation material upon the bed of muck and introducing water under pressure into the muck below the fill whereby it is rendered semi-fluid and the weight of the filling material acts to displace the muck beneath the fill.

In witness whereof I have hereunto set my hand.

SAMUEL D. SOLOMON.
